RAILWAY TRAFFIC CONTROLLING
APPARATUS

Herbert A. Wallace, Edgewood Borough, Pa., assignor to The Union Switch & Signal Company, Swissvale, Pa., a corporation of Pennsylvania

Application July 29, 1926, Serial No. 125,659

Renewed September 11, 1930

112 Claims.

(CL. 246—3)

My invention relates to railway traffic controlling apparatus, and more particularly, to centralized traffic control systems for railroads, and has for its object the provision of novel and improved means for safely controlling traffic governing devices, such as railway switches and signals, from a distant control point, such as a train dispatcher's office.

I will describe one form of railway traffic controlling apparatus embodying my invention, and will then point out the novel features thereof in claims.

In the accompanying drawings, Figs. 1 and 2 are diagrammatic views, which when placed end to end with Fig. 1 on the left, illustrate one form of railway traffic controlling apparatus embodying my invention.

Referring to the drawings, the reference characters *a* and *b* designate two stretches of railway track over which traffic at times moves in both directions. The tracks *a* and *b* are connected by a track switch *F*, operated by a power actuated mechanism or switch machine which I will describe hereinafter, so that when the switch is in its normal position, in which it is illustrated in the drawings, traffic can move without interference along track *a*. When switch *F* is reversed, however, traffic is permitted to move from track *b* into track *a*, or vice versa. The track rails *1* and *1a* of track *a* are divided by means of insulated joints *2*, into a plurality of track sections *A—B*, *B—C*, *C—D*, etc., track section *A—B* containing the switch *F*. By means of other insulated joints *2* that portion of track *b* adjacent the switch *F* is insulated from the rest of the track to form a track section *E—F*, and the rails of this section are connected directly with the corresponding rails of section *A—B* so that the rails of the sections of both tracks *a* and *b* which contain the switch *F*, are connected in parallel, and these sections will be referred to hereinafter collectively as the detector track section or as the switch track section.

Each track section of track *a* is provided with a track relay designated by the reference character *R* with a suitable distinguishing exponent and connected across the rails adjacent one end of the corresponding section. Track circuit current is supplied to the rails of each section by a battery designated by the reference character *d* and connected across the rails adjacent the opposite end of such section. As has been stated, the rails of section *E—F* are connected in parallel with the rails of section *A—B* so that a train

occupying any portion of the switch track section will shunt the relay *R*^A.

The reference character *M* designates an auxiliary relay which is arranged to be energized only when the track relays *R*^B and *R*^C are energized, the circuit for this relay passing from a suitable source of energy such as a battery *U*¹, through wire *3*, front contact *4* of relay *R*^C, wire *5*, front contact *6* of relay *R*^B, wire *7*, winding *8* of relay *M*, and common wire *9* back to battery *U*¹. Relay *M* is therefore de-energized when a train occupies either section *B—C* or section *C—D*. These two sections will be referred to hereinafter collectively as the approach section or as the approach zone, and relay *M*, since it becomes deenergized when a train approaches within a predetermined distance of switch *F*, will be referred to as the approach relay.

East bound traffic, that is, traffic moving from left to right over track *a* when switch *F* is normal, is governed by a home signal *S*^A, which as here shown is of the semaphore type and comprises a main blade *9* and a separate call-on blade *10*. Eastbound traffic moving from track *b* to track *a* when switch *F* is reversed is governed by a signal *S*^E located at point *E*. Westbound traffic, that is, traffic moving from right to left over track *a* when switch *F* is normal, is governed by a home signal *S*^B located at point *B* and comprising a main blade *9* and a call-on blade *10*. Signals *S*^A and *S*^B thus constitute a pair of opposing signals governing traffic moving in opposite directions over switch *F* when it occupies its normal position. The blade *10* of signal *S*^B also serves as the opposing signal for signal *S*^E so that this blade together with signal *S*^E constitutes a pair of opposing signals governing traffic moving over switch *F* reversed. Each blade of each of the signals *S*^A, *S*^E, and *S*^B is controlled by an electroresponsive mechanism, as indicated diagrammatically on the drawings by wires leading to the signal blade, these wires being included in an energizing circuit for the signal mechanism which is governed by means which will be described in detail hereinafter.

The reference character *S*^C designates an automatic signal located at point *C* and capable of displaying a proceed, a caution, or a stop indication, in accordance with traffic conditions in advance of the signal. Signal *S*^C is the usual "approach" signal, and is controlled by means forming no part of my present invention, and omitted from the drawings for the sake of simplicity.

The mechanisms for actuating the switch *F*

and all of the signals which are shown on Fig. 2 except signal S^C are actuated by a series of manually controlled electroresponsive devices here shown as polarized direct current relays each designated by the reference character K with a suitable distinguishing exponent. Relay K^1 controls the track switch F , relay K^2 controls the main signals for governing train movements in accordance with traffic conditions, relay K^3 controls the call-on signals, while relay K^4 is employed to put the signals to stop and to release the switch locking, as hereinafter described. The control relays K are operated by a series of pole-changers G^1 , G^2 , and G^3 , located at a distant control point such as in the office of the train dispatcher. The reference character H designates a clockwork time release of usual and well known form comprising a normally closed contact 11 and two other contacts comprising a pole-changer G^4 . When the time release H is operated contact 11 is opened and the pole-changer G^4 is reversed. When the time release H is released, a time interval elapses before the pole-changer G^4 returns to its normal position and contact 11 closes.

Located also in the control office are a plurality of manually operable levers or push buttons J^1 , J^2 , J^3 and J^4 , each comprising two normally open contacts 12 and 13 and a normally closed contact 14 . As will be described in detail hereinafter, the control relays K each respond to a different magnitude of current and they are selectively energized over the same line circuit by single brief impulses of current each of a distinctive character identified by its magnitude and polarity in accordance with the operation of the pole-changers G and the push buttons J .

Associated with the polarized switch control relay K^1 are two selector relays L^1_N and L^1_R . Two similar selector relays L^2_N and L^2_R are associated with the main signal control relay K^2 and relays L^3_N and L^3_R are associated with the call-on signal control relay K^3 . A single selector relay L^4_R is associated with control relay K^4 .

The switch machine for the track switch F comprises an operating mechanism including a motor having an armature 83 and a field winding 81 . When current of one polarity is supplied to the motor, the switch is moved to the normal position and when the polarity of the current supplied to the armature is reversed, the switch is moved to its reverse position. A number of contacts is controlled by the switch operating motor in accordance with the position of the switch so that contact $64-65-66$ is closed at all times except when the switch is in its extreme reverse position and contact $67-65-68$ is closed at all times except when the switch is in its extreme normal position. Contacts $203-204-205$ and contacts $207-204-206$ are closed when the switch occupies its normal or its reverse position respectively.

The reference characters Q^1 , Q^2 , Q^3 , and Q^4 designate four direct current transmitting relays which are controlled as will be described hereinafter.

Four polarized direct current indication relays each designated by the reference character N with an appropriate distinguishing exponent are located in the control office as shown on Fig. 1 and associated with each relay N is a polarized repeater relay designated by the reference character T with a distinguishing exponent. The relays N are similar to the relays K hereinbefore referred to and they are controlled over the

same pair of line wires as the relays K by single brief impulses of current of distinctive magnitude and polarity which are delivered to the line wires by the operation of the apparatus at the remote station. The repeater relays T control indicators as will be described hereinafter to apprise the operator of the condition of the apparatus.

I will assume that all polarized relays are so arranged that when the relays are energized in the normal direction their polarized contacts are swung to the left and that when the relays are energized in the reverse direction their polarized contacts are swung to the right. Polarized direct current relays of the usual type are so arranged that when the relay is de-energized the polarized armature remains in the position to which it was last moved.

Having thus described in general the arrangement and location of the various constituent parts comprising my invention, I will now proceed to explain the operation of the apparatus.

As here shown the track is unoccupied, switch F occupies its normal position, signal S^C indicates caution and all of the remaining signals indicate stop. I will first assume that the operator wishes to reverse switch F to permit traffic to proceed along the track b . To accomplish this result, he reverses pole-changer G^1 and operates push button J^1 . Current then flows from a suitable source of energy such as a battery U^2 , through wires 15 and 16 , contact 12 of push button J^1 , pole-changer G^1 , wire 17 , contact 11 of device H , wires 18 , 19 and 20 , front contact 21 of relay M , wire 22 , front contact 23 of relay Q^1 , wire 24 , back contact 25 of relay Q^2 , wire 26 , back contact 27 of relay Q^3 , wires 28 and 29 , front contact 30 of relay Q^4 , wire 31 , front contact 32 of relay R^A , wire 33 , winding of relay K^1 , wire 34 , winding of relay K^2 , wire 35 , winding of relay K^3 , wire 36 , winding of relay K^4 , wires 37 , 38 and 40 , resistances 40 , 41 and 42 , wire 43 , pole-changer G^1 , contact 13 of push button J^1 , and wires 44 and 45 , back to battery U^2 . It will be clear that current supplied over the circuit just traced traverses the windings of relays K^1 , K^2 , K^3 , and K^4 in series. These relays are constructed in such manner that they require progressively larger currents to cause the relays to become energized, relay K^1 becoming energized with the smallest value of current, and relay K^4 requiring the largest current. The circuit just traced for these relays includes resistances 40 , 41 and 42 , in series and the current supplied to the relays K over this circuit is sufficient to energize relay K^1 but is not sufficient to energize relays K^2 , K^3 , or K^4 . With the pole-changer G^1 reversed, the polarity of the current supplied to the circuit is such that relay K^1 becomes energized in the reverse direction.

When relay K^1 closes its reverse contact 58 , relay L^1_R is picked up by current which flows from battery U^3 , through wires 46 , 47 , and 48 , back contact 49 of relay K^4 , wires 50 and 51 , back contact 52 of relay K^3 , wire 53 , back contact 54 of relay K^2 , wire 55 , front contact 56 of relay K^1 , wire 57 , reverse contact 58 of relay K^1 , wires 59 and 60 , winding of relay L^1_R , and wire 61 , through common wire 8 to battery U^3 . The closing of front contact 72 of relay L^1_R completes a stick circuit for this relay from battery U^3 , through wires 46 , 62 , and 63 , contacts $64-65-66$, wire 69 , back contact 70 of relay L^1_N , wire 71 , front contact 72 of relay L^1_R , wires 73 and 60 , winding of relay L^1_R and wire 61 back to battery U^3 through common wire 8 . The operator may

then restore the push button J^1 to its normal position, terminating the impulse of current supplied to relays K and allowing relay K^1 to drop. The pick-up circuit for relay L^1R is thereby opened but the relay is subsequently maintained in its energized condition over its stick circuit, so as to store the switch operating impulse until the switch is operated to its reverse position in correspondence with the energized condition of relay L^1R . When relay L^1R picks up, the closing of front contact 81 completes a circuit for the switch operating mechanism and current flows from battery U^4 , through wire 74 , front contact 75 of relay L^4R , wire 76 , front contact 77 of relay R^A , wire 78 , front contact 81 of relay L^1R , wire 82 , armature 83 , wire 84 , back contact 85 of relay L^1N , wire 86 , field winding 87 , and common wire 8 back to battery U^3 . Negative terminal of battery U^4 is constantly connected with a positive terminal of battery U^3 so that when the circuit just traced is closed, the total voltage of batteries U^3 and U^4 is applied to the armature and field of the switch operating motor. Current supplied under these conditions to the motor is of such polarity that switch F is moved to the reverse position. When the switch has attained its full reverse position, contact $64-65-66$ opens, thereby interrupting the circuit for relay L^1R and allowing this relay to release. When this happens, the opening of front contact 81 of relay L^1R interrupts the operating circuit for the switch mechanism and de-energizes the motor.

I will now assume that the operator wishes to restore switch F to its normal position. To do this he restores pole changer G^1 to its normal position, in which it is illustrated in the drawings, and operates push button J^1 . Current from battery U^2 then flows through wires 15 and 16 , contact 12 of push button J^1 , pole changer G^1 , wire 43 , resistances 42 , 41 and 40 , through relays K^4 , K^3 , K^2 , and K^1 , front contact 32 of relay R^A , front contact 38 of relay Q^4 , back contact 27 of relay Q^3 , back contact 25 of relay Q^2 , front contact 23 of relay Q^1 , front contact 21 of relay M , and contact 11 of device H as before, and back through pole-changer G^1 , contact 13 of push button J^1 , and wires 44 and 45 , back to battery U^2 . It will be noted that the circuit for relays K which is closed when push button J^1 is operated and pole-changer G^1 is normal, is the same as hereinbefore traced when push button J^1 is operated with pole-changer G^1 reversed except that current flows through the circuit in opposite direction. When this circuit is closed, therefore, only relay K^1 picks up and the polarity of the current is such that this relay closes its normal contact. Current from battery U^3 then flows through wires 46 , 47 and 48 , back contact 49 of relay K^4 , wires 50 and 51 , back contact 52 of relay K^3 , wire 53 , back contact 54 of relay K^2 , wire 55 , front contact 56 of relay K^1 , wire 57 , normal contact 58 of relay K^1 , wires 88 and 89 , winding of relay L^1N and common wire 8 back to battery U^3 . Relay L^1N therefore becomes energized and completes a stick circuit over which current flows from battery U^3 , through wires 46 , 62 and 63 , contact $68-65-67$, wire 208 , back contact 72 of relay L^1R , wire 71 , front contact 70 of relay L^1N , wires 90 and 89 , winding of relay L^1N , and common wire 8 back to battery U^3 . The operator then restores push button J^1 to its normal position, interrupting the circuit for relay K^1 and permitting this relay to release. The pick-up circuit for relay L^1N is thereby interrupted, but the relay remains energized until

the switch returns to its normal position in correspondence with the energized condition of relay L^1N because current is now supplied to the relay over its stick circuit. When relay L^1N becomes energized, current flows from battery U^4 , through wire 74 , front contact 75 of relay L^4R , wire 76 , front contact 77 of relay R^A , wires 78 and 80 , front contact 85 of relay L^1N , wire 84 , armature 83 , wire 82 , back contact 81 of relay L^1R , wires 91 and 86 , field winding 87 and common wire 8 , back to battery U^3 . The combined voltage of batteries U^3 and U^4 is therefore applied to armature 83 and field winding 87 of the switch operating motor. The current then supplied to the motor is of such polarity that the motor returns the switch F to its normal position. When the switch attains its extreme normal position, contact $68-65-67$ opens, interrupting the stick circuit for relay L^1N and permitting the relay to release. The opening of front contact 85 of this relay interrupts the supply of current to the switch operating motor.

It should be pointed out that even after the switch mechanism has commenced to operate to move the switch from one position to the other, the operator may, by suitable operation of the push button J^1 and pole-changer G^1 , reverse the direction of movement of the switch during the transit of the switch. For example, I will assume that he has operated pole-changer G^1 and the push button J^1 to pick up relay L^1R and that the switch is being driven from its normal to its reverse position, and that before the stroke of the switch is completed he restores pole-changer G^1 to its normal position and operates J^1 . Relay K^1 then becomes energized in the normal direction, energizing relay L^1N . The opening of back contact 70 of this relay breaks the stick circuit for relay L^1R and allows that relay to drop. The stick circuit for relay L^1N is then closed from contact 72 of relay L^1R and the apparatus then operates to restore the switch to its normal position as will be clearly understood from the foregoing explanation.

Certain of the signals S are controlled in part by a circuit controller designated by the reference character P and operating in accordance with the position of the switch F . Contacts $138-138^a$, $120-120^a$, and $158-158^a$ are closed only when the switch occupies its normal position, and contacts $138-138^b$, $120-120^b$, and $158-158^b$ are closed only when the switch occupies its reverse position.

In explaining the operation of the signal control circuits, I will first assume that the switch F occupies its normal position to permit the movement of traffic along track a and that the operator wishes to clear blade 9 of signal S^A to permit eastbound traffic to proceed along the track a . To accomplish this result he operates push button J^2 with pole-changer G^2 in its normal position. A circuit is then closed over which current flows from battery U^2 , through wires 15 and 82 , push button J^2 , pole-changer G^2 , resistances 41 and 40 , and thence through relays K in series over the same circuit previously traced for these relays, returning through contact 11 of device H , wire 17 , pole-changer G^2 , push button J^2 , and wires 93 and 45 , back to battery U^2 . It will be noted that current supplied to the relays K over this circuit flows through resistances 41 and 40 . The parts are so proportioned that current supplied under these conditions is of sufficient magnitude to pick up both relays K^1 and K^2 and since pole-changer 75

G^2 is in the normal position the polarity of this current is such that relays K^1 and K^2 become energized in the normal direction. Normal contact 58 of relay K^1 is therefore closed but the pick-up circuit for relay L^1N is open at back contact 54 of relay K^2 , which relay is now energized. Relay L^1N therefore remains deenergized. The closing of front contact 54 of relay K^2 completes a pick-up circuit for relay L^2N and current flows from battery U^3 , through wires 46, 47, and 48, back contact 49 of relay K^4 , wires 50 and 51, back contact 52 of relay K^3 , wire 53, front contact 54 of relay K^2 , wire 94, back contact 95 of relay L^3N , wire 96, back contact 97 of relay L^3R , wire 98, normal contact 99 of relay K^2 , wires 100 and 101, winding of relay L^2N , wires 102 and 103, front contact 104 of relay R^A and common wire 8 back to battery U^3 . The closing of front contact 107 of relay L^2N completes a stick circuit for this relay, current flowing from battery U^3 , through wires 46, 47 and 48, back contact 49 of relay K^4 , wires 50, 105 and 106, front contact 107 of relay L^2N , wires 108 and 101, winding of relay L^2N , wires 102 and 103, front contact 104 of relay R^A and common wire 8 back to battery U^3 . The operator may then restore push button J^2 to its normal position, interrupting the circuit for relays K^1 and K^2 . These relays therefore release but relay L^2N remains in its energized condition by virtue of its stick circuit. With relay L^2N energized, blade 9 of signal S^A is cleared, current flowing from battery U^4 , through wires 74, 109 and 110, front contact 111 of relay L^2N , wires 112, 113, 114, 115, 116, 117 and 118, operating mechanism of blade 9 of signal S^A , wire 119, contact 120-120^a of circuit controller P, wire 121, front contact 122 of relay L^2N , wire 123, back contact 124 of relay L^2R , and wires 125, 126, 127, 128, 129, 47, and 46, back to battery U^4 . Signal S^A therefore indicates proceed to permit an eastbound train to proceed over the track a . I will assume that when the push button J^2 was operated to pick up relay L^2N , switch F was in the reverse position. Under these conditions it would be safe to permit eastbound traffic from track b to proceed through the stretch but it would be unsafe to clear blade 9 of signal S^A to permit traffic to proceed along track a from left to right. When the switch is in the reverse position, contact 120-120^a is open and contact 120-120^b is closed so that when the relay L^2N becomes energized, signal S^E is cleared, instead of blade 9 of signal S^A , the circuit for signal S^E passing from battery U^4 , through wires 74, 109 and 110, front contact 111 of relay L^2N , wires 112, 113, 114, and 130, operating mechanism of signal S^E , wires 131 and 132, contact 120-120^b of circuit controller P, wire 121, front contact 122 of relay L^2N , wire 123, back contact 124 of relay L^2R , and wires 125, 126, 127, 128, 129, 47, and 46, back to battery U^4 . It therefore follows that when relay L^2N is energized, a signal of one pair or the other is cleared for eastbound traffic through the stretch of track shown in the drawings but that the signal which is cleared depends upon the position of switch F, so that when the switch is normal, signal S^A clears and when the switch is reversed, signal S^E clears.

It is to be noted in this connection that contact 54 of relay K^2 serves as a two-position circuit controller to prevent the clearing of a signal and an operation of the switch at the same time, since this contact must be down to permit ener-

gization of the switch selecting relays and must be up to effect the energization of a signal selecting relay.

If the operator wishes to permit westbound traffic to pass the switch he reverses pole-changer G^2 and operates push button J^2 . Current is therefore supplied to the relays K in series as explained in connection with the operation of push button J^2 when pole-changer G^2 is normal. Relays K^1 and K^2 therefore pick up but relays K^3 and K^4 remain deenergized, the polarity of current supplied to the relays being such that relays K^1 and K^2 are energized in the reverse direction. Since back contact 54 of relay K^2 is open, relay L^2R does not become energized but a pick-up circuit is completed for relay L^2R over reverse contact 99 of relay K^2 , which circuit is similar to the pick-up circuit already closed for relay L^2N and will be readily understood from the drawings without tracing the circuit in detail. When relay L^2R becomes energized, the closing of front contact 133 thereon completes a stick circuit for this relay so that the relay is subsequently maintained in its energized condition independently of its pick-up circuit. The operator may then restore the push button J^2 to its original position, thereby de-energizing relays K^1 and K^2 without opening relay L^2R .

If switch F is normal, the energization of relay L^2R completes a circuit from battery U^4 , through wires 74, 109 and 110, front contact 155 of relay L^2R , wires 112, 134, 135 and 136, operating mechanism of blade 9 of signal S^B , wire 137, contact 138-138^a of circuit controller P, wire 139, front contact 124 of relay L^2R , wire 123, back contact 122 of relay L^2N , and wires 125, 126, 127, 128, 129, 47, and 46 back to battery U^4 . When this circuit is closed, blade 9 of signal S^B is cleared to permit traffic to proceed along track a past the switch F.

If switch F is reversed when relay L^2R picks up, current flows from battery U^4 , through wires 74, 109 and 110, front contact 155 of relay L^2R , wires 112, 134, 135, 140 and 141, operating mechanism of blade 10 of signal S^B , wires 142 and 143, contact 138-138^b of circuit controller P, wire 139, front contact 124 of relay L^2R , wire 123, back contact 122 of relay L^2N , wires 125, 126, 127, 128, 129, 47, and 46 back to battery U^4 . When this circuit is closed, therefore, blade 10 of signal S^B is cleared. It is therefore plain that the "call-on" blade 10 is used also for a low speed signal for permitting westbound traffic to proceed from track a to track b through the switch F.

It will be noticed that the circuits for each of the relays L^2N and L^2R include a front contact 104 of track relay R^A but this relay is de-energized when a train occupies any portion of the switch track circuit. It follows that relays L^2N and L^2R can be energized only when this track section is unoccupied. The signal operating circuits thus far described can therefore be completed to clear the corresponding signals only when the switch track circuit is unoccupied, and if one of the signals is cleared and a train enters the switch track circuit the signal will return immediately to stop, because of the consequent de-energization of relays L^2N or L^2R . Under certain conditions, however, it may be desirable to clear one of the signals when the switch track circuit is already occupied by a train. For example, it may occur that an eastbound train has passed signal S^A and the operator wishes to permit a following train to enter section A-B past signal S^A . The operator may permit this move-

ment of traffic by clearing the call-on blade 10 of signal S^A. To accomplish this result he operates push button J³ with pole-changer G³ normal. Current then flows from battery U², 5 through push button J³, pole-changer G³ and resistance 40 to relays K in series and back over pole-changer G³ and push button J³ to battery U². The circuit over which this current flows through the relays K is so similar to similar circuits 10 already traced that it is deemed unnecessary to trace the circuit in detail. It should be noted that current thus supplied to the relays K flows only through resistance 40 and not through resistances 42 and 41. The parts are so proportioned that under these conditions, 15 relays K¹, K², and K³ pick up and the polarity of the current is such that these relays become energized in the normal direction. The pick-up circuits for relays L¹_N and L²_N are open at back contact 20 tact 52 of relay K³ so that these relays remain de-energized but since relay K³ is now energized, a pick-up circuit is closed for relay L³_N from battery U³, through wires 46, 47 and 48, back contact 49 of relay K⁴, wires 50 and 51, front contact 25 tact 52 of relay K³, wire 144, back contact 145 of relay L²_N, wire 146, back contact 147 of relay L²_R, wire 148, normal contact 149 of relay K³, wires 150 and 151, winding of relay L³_N, and common wire 8 back to battery U³. It will be seen that 30 this circuit does not include a front contact of relay R^A and relay L³_N therefore picks up even though relay R^A is de-energized. The closing of relay L³_N completes a stick circuit for the relay over which current flows from battery U³, 35 through wires 46, 47 and 48, back contact 49 of relay K⁴, wires 50, 105 and 152, front contact 153 of relay L³_N, wires 154 and 151, winding of relay L³_N and common wire 8 to battery U³. The operator may then restore push button J³ to its 40 original position, thereby de-energizing relays K¹, K², and K³, but relay L³_N remains in its energized condition by virtue of its stick circuit just traced. With relay L³_N closed the call-on blade 10 of signal S^A is cleared, the circuit for this blade passing 45 from battery U⁴, through wires 74 and 109, front contact 156 of relay L³_N, wires 112, 113, 114, 115, 116, 117, and 118^a, operating mechanism of blade 10 of signal S^A, wire 157, contact 158—158^b of circuit controller P, wire 159, front contact 50 160 of relay L³_N, wire 161, back contact 162 of relay L³_R and wires 163, 126, 127, 128, 129, 47, and 46, back to battery U⁴. It will therefore be plain that the operator, by proper manipulation 55 of push button J³ and pole-changer G³ may clear the call-on blade of signal S^A to permit a train to enter the switch track section even though this section is already occupied so that it is impossible to clear the main blade 9 of signal S^A.

If the switch F is in its reverse position when 60 relay L³_N picks up, the operating circuit for the call-on blade 10 of signal S^A is open at front contact 158—158^b of circuit controller P and call-on blade of signal S^A cannot be cleared. Current can flow however, from battery U⁴, through wires 65 74 and 109, front contact 156 of relay L³_N, wires 112, 113, 114, and 130, operating mechanism of signal S^E, wires 131 and 164, contact 158—158^b of circuit controller P, wire 159, front contact 160 of relay L³_N, wire 161, back contact 162 of 70 relay L³_R and wires 163, 126, 128, 129, 47, and 46 back to battery U⁴. When switch F is reversed, therefore, if relay L³_N picks up, signal S^E clears to permit movement of eastbound traffic over track b, past the signal, even though the switch 75 track section is already occupied by a train.

In similar manner if the push button J³ is operated with pole-changer G³ reversed, current is supplied to the relays K in series through resistance 40, and relays K¹, K², and K³ pick up, but relay K⁴ remains de-energized. The polarity of the current then supplied to the relays is such that the relays close their reverse contacts. A pick-up circuit is therefore closed for relay L³_R similar to the pick-up circuit just traced for relay L³_N. This pick-up circuit does not include a front contact of relay R^A, and therefore relay L³_R becomes energized, even though relay R^A is de-energized due to the presence of a train in the switch track section. When front contact 165 of relay L³_R closes, a stick circuit is completed for this relay similar to the stick circuit hereinbefore traced for relay L³_N. The operator may then restore push button J³ to its original position, de-energizing relays K¹, K², and K³, but relay L³_R remains picked up over its stick circuit. With relay L³_R energized, current flows from battery U⁴, through wires 74 and 109, front contact 166 of relay L³_R, wires 112, 134, 135, 140, and 141, operating mechanism of call-on blade 10 of signal S^B, wires 142 and 167, front contact 162 of relay L³_R, wire 161, back contact 160 of relay L³_N, and wires 163, 126, 127, 128, 129, 47, and 46 back to battery U⁴. It therefore follows that the energization of relay L³_R clears the call-on blade of signal S^B irrespective of the position of switch F so that when the push button J³ is operated with pole-changer G³ reversed to clear the blade 10 of signal S^B eastbound traffic is allowed to pass signal S^B even though the switch track section is already occupied by a train which de-energizes relay R^A and makes it impossible to clear the main blade 9 of signal S^B.

It will be seen from the foregoing that the energizing circuits for the signals are so interlocked as to prevent the clearing of two opposing signals at the same time. Thus, for example, the circuit for blade 9 of signal S^A as hereinbefore traced includes front contact 122 of relay L²_N, the connecting wire 123, and back contact 124 of relay L²_R, while the energizing circuit for blade 9 of the opposing signal S^B includes back contact 122 and front contact 124, and furthermore, the circuits for signal S^E and blade 10 of signal S^B which control traffic movements over switch F reversed are similarly controlled over contacts 160 and 162 of relays L³_N and L³_R. In addition, the two pairs of stick relays L are interlocked so that only one stick relay can be picked up at a time, because the pickup circuit for each relay of a pair includes back contacts of both relays of the other pair and the pickup circuits for the two relays of the same pair include opposite polar contacts of the same control relay K. Finally, the interlocked circuits 50 include contacts of the switch circuit controller P which are responsive to the operation of the switch control relay K¹, so that the clearing of a signal is prevented even though the signal control means is operated, unless the switch is in the proper position to permit the clearing of the signal selected by the signal control relay which is energized.

It will be noted that the circuits for relays L²_N, L²_R, L³_N, and L³_R all include a back contact 49 of relay K⁴. If, therefore, the operator has energized any of these relays L to clear a corresponding trackway signal and wishes to restore that signal to stop, he may do so by energizing relay K⁴. This may be accomplished by operat- 75

ing push button J⁴. I will assume that the time release H occupies its normal position in which it is illustrated in the drawings when the push button J⁴ is operated. Current then flows from 5 battery U², through push button J⁴, and the pole-changer G⁴ of device H, to relays K in series and back through the pole-changer G⁴ and push button J⁴ to battery U² over a circuit which is similar to other circuits previously traced for relays K. It will be noted that when this circuit 10 is closed none of the resistances 42, 41, or 40 is interposed in series with the relays. The full voltages of battery U² is therefore applied to relays K and all of these relays become energized. 15 With device H in its normal position, the polarity of this current is such that the relays K become energized in their normal directions. Circuits for relays L²_N, L²_R, L³_N, and L³_R are all opened at back contact 49 of relay K⁴ so that if any of these 20 relays were energized prior to operation of the push button J⁴ that relay now becomes de-energized, thereby interrupting the operating circuit for its associated signal and restoring the signal to stop. It follows that when relay K⁴ is energized all of the signals indicate stop. 25

Relay L⁴_R is provided with a pick up circuit one branch of which may be traced from battery U¹, through wires 3 and 209, circuit controller 168 operated by signal S^C, wire 169, circuit controller 170 operated by blade 10 of signal S^B, wire 171, circuit controller 172 operated by blade 9 of signal S^B, wire 173, circuit controller 174 operated by signal S^E, wire 175, circuit controller 176 operated by blade 9 of signal S^A, wire 177, 30 circuit controller 178 operated by blade 10 of signal S^A, wire 179, back contact 180 of relay L²_N, wire 181, back contact 182 of relay L²_R, wire 183, back contact 184 of relay L³_N, wire 185, back contact 186 of relay L³_R, wire 187, winding of 35 relay L⁴_R, wires 188, 189, 190 and 200, front contact 201 of relay M and common wire 8 back to battery U¹. The circuit just traced is provided with a branch which passes from wire 189, through wire 193, back contact 194 of track relay R^A and common wire 8 back to battery U¹. Another branch is provided for the pick up circuit of relay L⁴_R, from wire 188, through wire 195, reverse contact 197 of relay K⁴, wire 198, 40 front contact 199 of relay K⁴ and back to common wire 8 to the battery U¹. Still another branch is provided for the circuit for relay L⁴_R, from wire 190, through wire 191, front contact 192 of relay L⁴_R and back through common wire 8 to battery U¹. It will be seen that this branch 45 last traced comprises a stick circuit for relay L⁴_R which is closed only after the relay has already become energized by current over some other branch of its circuit. Under normal conditions, the approach relay M is energized, the track relays R^B and R^C being normally energized, and if all the signal relays are deenergized and the signals are at stop relay L⁴_R is energized over the circuit first traced for this relay including front contact 201 of relay M. The stick circuit for relay L⁴_R is also closed, so that relay L⁴_R will remain energized if a train occupies section C—D, and relay M becomes de-energized. However, when signal S^C indicates proceed or any of the other signals is cleared, relay L⁴_R becomes de-energized. It will be apparent that relay L⁴_R will become reenergized when a train enters the detector section and the signal is put to stop automatically due to the closing of back contact 194 of track relay R^A, and will also become reenergized when a signal is manually put

to stop, provided the approach section is unoccupied so that front contact 201 of relay M is closed. When relay L⁴_R is de-energized front contact 75 is open, and the circuit for the switch operating mechanism is therefore interrupted. It follows that relay L⁴_R serves as an approach locking relay, and that when relay L⁴_R is de-energized, the apparatus provides a condition analogous to the well known approach locking which prevents operation of the switch if a signal is manually put to stop when a train is approaching the switch unless the operator takes special steps to release the approach locking. A signal may be put to stop manually by operating the push button J⁴ to energize relay K⁴, as has been explained in detail hereinbefore. If a train is approaching, the operator will be apprised of that fact by the condition of his indication apparatus as hereinafter explained, and in that case he operates the clockwork time release H to reverse pole-changer G⁴. He then operates the push button J⁴, to energize relay K⁴, and then allows the clockwork time release to return to its original position. Due to the slow return characteristics of the device H, a considerable interval of time elapses before the pole-changer G⁴ returns to its normal position. If push button J⁴ is operated when the pole-changer is reversed, current is supplied through the push button J⁴ and the pole-changer G⁴ to relays K in series over a circuit which is similar to that previously described for these relays when pole changer G⁴ is normal and push button J⁴ is operated, the only difference being that when G⁴ is reversed the current supplied to relays K is of such polarity that the relays become energized in the reverse direction. Relay L⁴_R therefore picks up and closes its stick circuit including its own front contact 192. The closing of front contact 75 of relay L⁴_R again permits the circuit to be closed for the switch operating mechanism in response to an operation of relay L¹_N or L¹_R, provided the switch section is unoccupied so that contact 77 of the detector track relay R^A is closed. 40

It should be observed however, that the switch remains locked and the signals are held at stop during the time interval required for the device H to return to its normal position, after relay L⁴_R has been energized, because the checking contact 11 of this device is open and under this condition it is impossible to operate any of the selecting relays L by manipulation of the push buttons J¹, J² or J³, because the circuit for relays K which is closed by the operation of these push buttons includes the normal contact 11 of device H. If the device H and push button J⁴ are operated to energize relay L⁴_R when section B—C or section C—D is occupied by a westbound train to release the approach locking the time interval required for the return of device H to its normal position imposes a delay in the restoration of the operator's control over the switch to insure that switch F will not be operated immediately in front of a rapidly moving train. 55

Although the apparatus herein disclosed provides for approach locking only for westbound traffic I do not wish to limit myself to this arrangement, as similar circuits could be arranged for providing approach locking for eastbound traffic in the same manner as here provided for westbound traffic. 60

As suggested hereinbefore, I have provided indication means arranged to inform the operator concerning the condition of the trackway governing devices controlled by the pole-changers 75

G and push buttons J. For example, two visual indicators 226 and 231, here shown as electric lamps having illuminated covers G and R, are lighted when the switch track section is unoccupied or occupied, respectively. Other indicators give the operator further information concerning the condition of the apparatus as will appear from the following description.

Relay R^A is a two-position relay and is normally energized when the switch track section is unoccupied as has been explained. Relay Q⁴ is a slow pick up and slow release repeating relay which is controlled by front contact 104 of relay R^A, and is therefore energized when relay R^A is picked up. In explaining the return indication of the condition of the switch track section, I will first assume that a train enters the section, thereby de-energizing relay R^A. The opening of front contact 104 of relay R^A de-energizes relay Q⁴, but due to the slow releasing characteristics of the latter relay a time interval elapses during which relay R^A is released and relay Q⁴ is picked up. During this brief interval an indication circuit is closed over which current flows from battery U⁵, through wires 210, 211, and 227, back contact 228 of relay R^A, wire 212, front contact 213 of relay Q⁴, wires 214, 215 and 38, thence through contact 14 of each push button J and the winding of each relay N to wire 19, and through wire 29, front contact 21 of relay M, wire 22, front contact 23 of relay Q¹, wire 24, back contact 25 of relay Q², wire 26, back contact 27 of relay Q³, wires 28 and 216, front contact 217 of relay Q⁴, wire 218, back contact 219 of relay R^A, and wires 220 and 221 back to battery U⁵. When this circuit is closed, the full voltage of battery U⁵ is applied to relays N¹, N², N³, and N⁴ in series and these relays N are constructed similar to relays K to require currents of different magnitudes to energize the relays. When the circuit just traced is closed, however, relays N all become energized and the polarity of the current supplied to the relays is such that they close their reverse contacts. With relay N⁴ energized in the reverse direction, front contact 222 is closed and the reverse contacts 223 and 224 are also closed so that relay T⁴ is energized in the reverse direction by current from battery U⁶, over circuits which will be obvious from the drawings. Lamp 226 is therefore lighted to indicate that the switch track section is occupied. As soon as the time interval required for operation of relay Q⁴ elapses, this relay drops, thereby interrupting the circuit over which relay N⁴ was energized but relay T⁴ maintains its reverse contact closed and lamp 226 is constantly energized.

If, now, relay R^A becomes energized, as when the train leaves the switch track section, a time interval elapses before relay Q⁴ closes its front contacts and during this time interval relay R^A is picked up and relay Q⁴ is released. During this brief interval, current from battery U⁵ flows over front contact 228 of relay R^A and back contact 217 of relay Q⁴ through relays N in series, over a circuit similar to that just traced for these relays. It will be seen that the full voltage of battery U⁶ is applied to relays N but the polarity of the current flowing in the relays is such that they are energized in their normal direction. Relay N⁴ being energized in the normal direction, relay T⁴ is also picked up in the normal direction so that lamp 231 is lighted to indicate that the switch track section is unoccupied. After a brief interval, relay Q⁴ picks up,

thereby interrupting the circuit for relays N but the normal contacts of relay T⁴ remain closed so that lamp 231 remains lighted.

Located in the control office are two lamps 246 and 252 provided with visual indicators N and R which are lighted when the switch F occupies its normal or reverse position, respectively. In explaining the control of lamps 246 and 252, I will first assume that relay L¹R is energized, thereby completing the circuit for the armature 83 and field winding 87 of the switch operating motor, and that the switch is being moved from its normal to its reverse position. For a brief interval, near the end of the transit of the switch, a circuit is closed for relay Q³ from battery U³, through wires 46, 47, 129, 128, 127, and 232, winding of relay Q³, wire 233, contact 207—204—206, wire 234, front contact 235 of relay L¹R and common wire 8 back to battery U³. Relay Q³ is therefore energized and the current supplied to this relay over the circuit just traced is of such polarity that the relay becomes energized in the reverse direction. When this happens a circuit is closed from battery U⁵, through wires 218, 211, and 236, front contact 231 of relay Q³, wire 238, reverse contact 239 of relay Q³, wires 240, 215, and 38, thence through contact 14 of each push button J and the winding of each relay N in series and back through wires 19 and 26 and 242, resistance 243, reverse contact 251 of relay Q³, wire 248, front contact 249 of relay Q³, and wires 250, and 221 back to battery U⁵. It will be manifest that when the circuit just traced is closed, current is supplied from battery U⁵ to relays N in series, through resistance 243. The relays are so proportioned that under these conditions, relays N¹, N², and N³ pick up in the reverse direction but relay N⁴ remains de-energized. With relay N³ energized in the reverse direction, relay T³ also becomes energized in the reverse direction, thereby lighting lamp 246 to indicate that the switch has moved to its reverse position. Of course front contact 235 of relay L¹R opens as soon as this relay releases at the end of the transit of the switch, as has been explained in detail hereinbefore, but relay T³, having once been energized in the reverse direction, holds its reverse contact closed so that lamp 246 remains lighted.

In similar fashion when relay L¹R is energized and the switch is being returned to its normal position, a temporary circuit is closed for relay Q³ from battery U⁴, through wire 74, front contact 75 of relay L¹R, wire 76, front contact 77 of relay R^A, wires 73, 89 and 79, front contact 247 of relay L¹N, wire 248, contact 205—204—203, wire 233, winding of relay Q³, and wires 232, 127, 128, 129, 55 47, and 46, back to battery U³. Relay Q³ therefore becomes energized in the normal direction for a brief interval and during this interval, current from battery U⁵ flows through resistance 243 to relays N in series over a circuit which is similar to that traced above for reverse energization of relay Q³. Relays N¹, N², and N³ therefore become energized in the normal directions and relay T³ also picks up in the normal direction, thereby lighting lamp 252 to indicate that the switch has been restored to its normal position.

The operator is informed concerning the signal positions by means of the signal indicators 257 and 258, here shown as lamps having illuminated covers carrying representations of signals in the stop and proceed positions, respectively. In explaining the control of the indicators 256 and 257, I will first assume that the operator has taken the proper steps to clear one of the trackway signals. For purposes of explanation I will assume that

relay L^2_R has been energized to clear main blade 9 of signal S^B . As the signal blade approaches its clear position a contact 253—253^a controlled by the signal blade is closed for a brief interval. 5 During this interval, a circuit is closed for relay Q^2 from battery U^4 , through wires 74, 109, and 110, front contact 155 of relay L^2_R , wires 112 and 134, contact 253—253^a operated by signals S^B , wires 254 and 255, winding of relay Q^2 , wires 128, 129, 10 41 and 46, back to battery U^4 . Relay Q^2 therefore becomes energized in the reverse direction for a brief interval of time and during this interval an indication circuit is closed, supplying current from battery U^5 through resistances 243 and 244 to 15 relays N^1 in series. This indication circuit is so similar to the circuits controlled by relay Q^3 that it is deemed unnecessary to trace the circuit in detail. When this circuit is closed, however, relays N^1 and N^2 become energized in the reverse direction 20 so that relay T^2 also becomes energized in the reverse direction, thereby lighting indicator 256 to inform the dispatcher that blade 9 of signal S^B has cleared. Of course the indication circuit controlled by relay N^2 is closed only while this relay 25 is energized, but relay T^2 holds its reverse contact closed so that the indicator 256 remains lighted.

It will be observed that the circuit just traced for relay Q^2 included front contact 155 of relay 30 L^2_R , but in parallel with this contact are front contact 151 of relay L^2_N , front contact 156 of relay L^3_N and front contact 166 of relay L^3_R . It therefore follows that when the operator has energized any of these relays to clear corresponding signals 35 the indicator 256 apprises him of the fact that the signal has actually moved to the clear position.

Returning to the assumption that relay L^2_R is energized and that blade 9 of signal S^B has cleared, I will assume that the signal is returned 40 to its stop position by de-energizing the relay L^2_R . As the blade approaches its stop position, a contact 253—253^b is closed for a brief interval and during this interval current flows from battery U^3 , through wires 46, 47, 129 and 128, winding of relay Q^2 , wires 255 and 254, contact 45 253—253^b operated by signal S^B , wire 274, back contact 265 of relay L^2_N , back contact 266 of relay L^2_R , wire 267, back contact 268 of relay L^2_N , back contact 269 of relay L^3_R and common 50 wire 8 back to battery U^3 . Relay Q^2 then becomes energized in the normal direction and during the interval that this relay is thus energized, current from battery U^5 flows through resistances 55 243 and 244 and relays N in series in such direction that relays N^1 and N^2 are energized in the normal direction. Relay T^2 therefore picks up in its normal direction, lighting indicator 257 to inform the dispatcher that the signal has returned to its stop position.

60 The lamps 264 and 263 inform the operator concerning the condition of the approach locking apparatus. These lamps are controlled partly by relay Q^1 , which is a slow-acting relay controlled by front contact 270 of relay M in such manner that when relay M is energized, relay Q^1 is also energized. In explaining the operation of the approach indication, I will first assume that relay M becomes de-energized as by the entrance of a train into section C—D. This relay therefore 65 opens, but relay Q^1 , due to its slow-releasing characteristics, holds its front contacts closed for a brief interval of time. During this time interval, current from battery U^5 flows over wires 210, 211, 236, back contact 261 of relay M and front 70 contact 260 of relay Q^1 , wires 240, 215 and 38,

thence through relays N in series over circuits which are similar to the circuits controlled by relays R^4 and Q^4 for indicating the condition of the switch track section. When this circuit is closed, resistances 243, 244, and 245 are all included in series with the relays N and the parts are so proportioned that under these conditions, relay N^1 becomes energized in the reverse direction, but the remaining relays N do not pick up. Relay T^1 therefore picks up in the reverse direction. 10 When relay T^1 becomes energized, a single stroke bell 253 is operated by current supplied from battery U^6 , over front contact 271 of relay T^1 , thereby calling the attention of the operator to a change in the condition of the approach locking apparatus. When the relay is energized in the reverse direction, lamp 263 is lighted to indicate that the approach section is occupied. When the approach section is vacated, relay M becomes energized, but relay Q^1 15 does not close its front contact for a time interval and during this interval, current from battery U^5 is supplied to relays N , through resistances 243, 244, and 245, over front contact 261 of relay M and back contact 260^a of relay Q^1 . The current thus supplied to relays N picks up only relay N^1 in the normal direction, thereby energizing relay T^1 in the normal direction and lighting lamp 264. It should be pointed out that while I have, in the apparatus here shown and 20 described, accomplished the variations in current strength supplied to relays K and relays N by means of resistances of different values interposed in series with these relays, this particular arrangement is not essential and any other means 25 could be used for varying the strength of the current through the relays. It should also be pointed out that my invention is not limited to the control of the particular railway governing devices illustrated in this application, but that 30 any other suitable governing devices could be controlled from the dispatcher's office in similar manner.

Although I have herein shown and described 35 only one form of railway traffic controlling apparatus embodying my invention, it is understood that various changes and modifications may be made therein within the scope of the appended 40 claims without departing from the spirit and scope of my invention.

Having thus described my invention, what I 45 claim is:

1. In combination, a stretch of railway track, a plurality of traffic governing devices for said stretch separately controlled from a distant point, 50 a plurality of polarized relays located at such point and requiring currents of different magnitudes to energize the relays, a source of energy for supplying current to all said relays, means controlled by said traffic governing devices for 55 controlling the polarity and magnitude of the current supplied to said relays, and a plurality of indicators located at such distant point and selectively controlled by said relays.

2. In combination with a single pair of line 60 wires, a group of relays normally connected with said wires, a second group of relays normally connected with said line wires, manually operable means for at times supplying current to said line wires for selectively operating the relays of 65 the second group, and means controlled by the relays of such second group for at times supplying current to said line wires for selectively operating the relays of said first group.

3. In combination a plurality of relays con- 75

nected in an electrical circuit, means for at times removing certain of said relays from said circuit and for supplying current to the circuit at such times for selectively operating the remaining relays, and means controlled by such remaining relays for at times supplying current to said circuit for selectively operating said certain relays.

4. In combination with a traffic governing device a first relay for controlling said device, means including a single pair of line wires for controlling said relay from a distant point, a plurality of other relays normally connected with said line wires at such distant point, means controlled by said device and by traffic conditions adjacent said device for at times supplying current to said line wires for selectively operating said other relays, indication means selectively controlled by such other relays, and means for disconnecting said other relays from the line wires when current is being supplied to the line wires for controlling said first relay.

5. In combination, a stretch of railway track, a track relay responsive to traffic conditions in said stretch, a traffic governing device for said stretch, means including a single pair of line wires for controlling said device from a distant point, a polarized relay at times connected with said line wires adjacent such distant point, and means controlled by said track relay for supplying said line wires with current of one polarity or the other according as a train enters or leaves said stretch.

6. In combination, a stretch of railway track, a track relay responsive to traffic conditions in said stretch, a traffic governing device for said stretch, means including a single pair of line wires for controlling said device from a distant point, a polarized relay at times connected with said line wires adjacent such distant point, a slow acting relay controlled by said track relay, and means controlled by said track relay and by said slow acting relay for supplying said line wires with current of one polarity or the other according as a train enters or leaves said stretch.

45 7. In combination a plurality of traffic governing devices, means including a single pair of line wires for selectively controlling said devices from a distant point, a plurality of relays located at such distant point and selectively responsive to the character of the current supplied thereto, means for normally connecting each of said relays with said line wires, and means effective upon an operation of any of said devices to supply said line wires with current of a different character depending upon the device which is operated.

8. In combination, a plurality of traffic governing devices, means for selectively controlling said devices from a distant point over a single pair of line wires, a first group of relays located at such distant point and selectively responsive to the character of the current supplied thereto, means for normally connecting each relay of said first group with said line wires, a second group of relays selectively controlled in accordance with the condition of said devices, and means controlled by each relay of said second group for at times supplying the line wires with current of a different character for selectively operating the relays of said first group.

9. In combination, a railway traffic governing device, control means for moving said device to one position or the other controlled from a distant point over a single pair of line wires, a signal adjacent said device, locking means effec-

tive if said signal is manually put to stop when a train is approaching within a predetermined distance of said device to render said control means ineffective, and means manually controlled over said line wires and effective when the signal is at stop for rendering said locking means ineffective.

5 10. In combination, a railway traffic governing device, means for moving said device to one position or the other controlled from a distant point over a single pair of line wires, a signal adjacent 10 said device, a contact arranged when open to prevent the control of said device from said distant point, means effective to open said contact when the signal is cleared and to maintain it open if the signal is put to stop when a train is 15 approaching within a predetermined distance of said device, and means located at said distant point for subsequently closing said contact over said line wires.

20 11. In combination with a railway track switch, control means for moving said switch to its normal or its reverse position controlled from a distant point over a single pair of line wires, a signal governing the movement of traffic over the switch, locking means rendered effective when the signal is cleared and remaining effective if the signal is manually put to stop when a train is approaching within a predetermined distance of said switch to render said control 25 means ineffective, means for manually controlling said signal, and other means controlled from said distant point over said line wires and effective at the expiration of a time interval following an operation of such other means after said signal 30 has been put to stop to render said locking means ineffective.

35 12. In combination with a railway track switch, a relay adjacent said switch and controlled from a distant point, means controlled by said relay for operating said switch, a signal governing the movement of traffic over the switch, locking means rendered effective when the signal is cleared and remaining effective if the signal is manually put to stop when a train is approaching within a predetermined distance of said switch to prevent the control of said switch by said relay, means for manually controlling said signal, other means controlled from said distant point for rendering said locking means ineffective, 40 and means operating for a time interval after actuation of said other means to prevent operation of said relay from said distant point.

45 13. In combination with a railway switch, a first and a second relay selectively controlled from a point remote from the switch, a normally energized relay arranged to be deenergized when a train is approaching said switch, a fourth relay having a circuit including a front contact of said normally energized relay, a branch around said front contact including a contact of said second relay, and means controlled by said first relay and effective when said fourth relay is energized to operate said switch.

55 14. In combination with a plurality of traffic governing devices, a first group of relays for separately controlling said devices and requiring currents of different characters to operate the relays, means controlled from a distant point for at times supplying currents of different 60 characters to all said relays over a single pair of line wires, a second group of relays selectively controlled by said devices and by traffic conditions adjacent said devices, a third group of relays normally connected with said line wires at 70 75

- said distant point and requiring currents of different characters to operate the relays, and means controlled by the relays of the second group for at times supplying said line wires with currents of different characters to selectively control the relays of the third group.
15. In combination, a stretch of railway track, a track relay responsive to traffic conditions in said stretch, a traffic governing device for said stretch, means including a single pair of line wires for controlling said device from a distant point, a relay controlled by said track relay, and means controlled by said last mentioned relay and said track relay for supplying said line wires 15 with current of one polarity or the other according as a train enters or leaves said stretch.
16. In combination with a single set of line wires, a first group of relays normally connected with said line wires, a second group of relays 20 normally connected with said line wires, means controlled by said first group of relays for momentarily supplying current to said second group, means controlled by said second group of relays for momentarily supplying current to said 25 first group, a third group of relays, means controlled by the relays of said first group for momentarily energizing the relays of said third group, means included in said third group for continuing each relay in its last operated position, indicating means controlled by the relays of said third group, a fourth group of relays normally energized by said second group, means included in said fourth group for continuing each relay in its last operated position, and traffic 30 controlling devices controlled by the relays of said fourth group.
17. In combination, a plurality of relays connected in an electrical circuit, means for at times removing certain of said relays from said 45 circuit and for momentarily supplying current to the circuit at such times for selectively operating the remaining relays, and means controlled by such remaining relays for at times supplying current to said circuit for selectively operating said certain relays.
18. In combination, an office and a station connected by a single line circuit, means at the office for supplying a single brief impulse of energy of a distinctive character to said line 50 circuit, a traffic governing device at said station, means responsive to said single impulse to initiate movement of said device and to complete such movement after the termination of said impulse, and indication means at said office controlled over 55 said line circuit and responsive to traffic conditions adjacent said station.
19. In combination, an office and a station connected by a single line circuit, means located at the office for supplying said line circuit with brief current impulses of different characters, a stick relay at the station, means responsive to an impulse of a predetermined character in said line circuit for energizing said stick relay, means for subsequently holding said stick relay energized after the termination of said impulse, a traffic governing device at said station controlled by said stick relay, and indication means at the office controlled over said line circuit in accordance with traffic conditions adjacent said 70 station.
20. In combination, an office and a station connected by a single line circuit, means located at the office for supplying said line circuit with brief current impulses of different characters, a stick relay at the station, means re-

sponsive to an impulse of a predetermined character in said line circuit for energizing said stick relay, means for subsequently holding said stick relay energized after the termination of said impulse, a traffic governing device at said station controlled by said stick relay, and indication means at the office controlled over said line circuit in accordance with the condition of said device.

21. In combination, an office and a station connected by a single line circuit, a relay located at said station and connected in said circuit, means at the office for at times supplying current impulses to said circuit for controlling said line relay, a stick relay at said station, means effective upon a single operation of said line relay in response to a current impulse in said line circuit to energize said stick relay, means for subsequently holding said stick relay energized after the termination of said impulse, transmitting means at said station for at times supplying indication current to said line circuit, means at said office selectively controlled by such indication current, and means for removing said line relay from said circuit when indication current is being supplied to such circuit.

22. In combination, an office and a station connected by a single line circuit, a traffic governing device at said station, means responsive to traffic conditions adjacent said station for at times supplying a single indication impulse to said line circuit, indication means at the office responsive to said indication impulse in the line circuit to display a distinctive indication which persists after the termination of said indication impulse, transmitting means at the office for at times supplying current to said line circuit for controlling said device, and apparatus for preventing said indication means from responding to current supplied to said line circuit by said transmitting means.

23. In combination with an office and a station connected by a line circuit, an office relay and a station relay normally connected in said circuit, means at the office for at times removing said office relay from said circuit and supplying a control current impulse to the line circuit for operating said station relay, a traffic governing device at the station, means responsive to an operation of said station relay for initiating a control of said device and for continuing such control after the termination of said control impulse, means at the station for at times removing said station relay from said circuit and supplying an indication current impulse to said circuit for operating said office relay, and means at the office for displaying a distinctive indication in response to operation of said office relay and for continuing such indication after the termination of said indication impulse.

24. In combination, an office and a station connected by a line circuit, an office relay normally connected in said circuit, means at said station for supplying only a single impulse of current to said line circuit to operate said office relay, an indication device, and a second relay controlled by said office relay and operating in response to an energization of said office relay by said single impulse to produce persistent operation of said device after the termination of said impulse.

25. In combination, an office and a station connected by a line circuit, a plurality of traffic governing devices at said station, means responsive to a change in the condition of any said

device to characteristically and momentarily control said line circuit, means at the office selectively responsive to such control of the line circuit to display a distinctive indication, and means 5 for continuing such indication after the termination of the control which caused it.

26. In combination, an office and a station connected by a line circuit, a first group of relays at the office all included in said circuit and 10 selectively responsive to the character of the current supplied thereto, a second group of relays selectively controlled by the relays of said first group, indication means selectively controlled by the relays of said second group, and means at said 15 station for supplying said line circuit with current impulses of different characters.

27. In combination, an office and a station connected by a line circuit, means at the station for momentarily and characteristically controlling said line circuit in accordance with traffic 20 conditions adjacent such station, and means at the office selectively responsive to such momentary control of the line circuit to display a continuous indication.

28. In combination, an office and a station connected by a line circuit, a traffic governing device at said station, means responsive to a change in the condition of said device to momentarily and characteristically control said line circuit, and means at the office selectively responsive to such momentary control of the line circuit to display a continuous indication.

29. In combination, an office and a station connected by a line circuit, a plurality of traffic 35 governing devices at the station, means responsive to a change in the condition of any said device to impose upon said circuit a momentary control, the character of which depends upon the particular device and its condition, and means at the office selectively responsive to such momentary control of the line circuit to display continuous indications.

30. In combination, an office and a station connected by a line circuit, a section of railway track 45 located at said station, traffic governing devices adjacent said section, means located at said office for controlling said devices over said line circuit, means responsive to the approach of a train to said section to momentarily control said line circuit, and means at said office responsive to such 50 momentary control of said line circuit to give a continuous approach indication.

31. In combination, an office and a station connected by a line circuit, a section of railway track 55 located at said station, traffic governing devices adjacent said section, means located at said office for controlling said devices over said line circuit, locking means at said station for at times modifying the control of said devices by said office 60 means in accordance with traffic conditions, and means controlled over said line circuit for continuously indicating the condition of said locking means at said office.

32. In combination, an office and a station connected by a line circuit, a section of railway track 65 located at said station, two signals for governing traffic over said section, means at the office for imposing distinctive momentary controls upon said line circuit, means at the station responsive to one such momentary control of the line circuit to clear one of said signals and hold such one signal clear provided said section is unoccupied, and means also at the station and responsive to another momentary control of the line circuit 70 to clear the other said signal and hold such other

signal clear independent of the condition of the track circuit.

33. In combination, an electrical device responsive to the polarity of current supplied thereto, a plurality of electroresponsive devices including 5 said electrical device, a manually operable device, means controlled by said manually operable device for controlling the energization of said electroresponsive devices successively and of said electrical device by current of a given polarity, 10 a second manually operable device, and means controlled by said second manually operable device independently of said first manually operable device for energizing said electrical device by current of the opposite polarity. 15

34. In combination, an electrical device responsive to the polarity of current supplied thereto, a plurality of electroresponsive devices including 20 said electrical device, a manually operable device, means controlled by said manually operable device for controlling the energization of said electroresponsive devices successively and of said electrical device by current of a given polarity, and means controlled independently of said manually operable device for energizing said electrical 25 device by current of the opposite polarity.

35. In combination, a plurality of electroresponsive devices, a manually operable device, a second manually operable device, a stick relay, a pick-up circuit for said stick relay controlled 30 by said first manually operable device, a stick circuit for said stick relay controlled by said second manually operable device, and means controlled by said stick relay for energizing said electroresponsive devices successively. 35

36. In combination, a plurality of partly interinclusive groups of electroresponsive devices, a manually operable device for each of said groups, a second manually operable device for each of said groups, a stick relay for each of said groups, 40 a pick-up circuit for each of said stick relays controlled by the said first manually operable device for the same group, a stick circuit for each of said stick relays controlled by the said second manually operable device for the same group, 45 and means controlled by each of said stick relays for energizing the electroresponsive devices in its group successively.

37. In combination with a railway track switch, a signal for governing traffic over said switch, a 50 relay for controlling said signal, and a locking circuit including in series a back contact of said relay and a contact operated by said signal and closed when said signal is at stop for controlling said switch. 55

38. In combination, a stretch of railway track, a signal for governing traffic movements over said stretch, control means for said signal, a stick relay controlled by said signal control means and by traffic conditions, a second signal for governing traffic movements over said stretch, and means controlled by said stick relay for controlling said second signal. 60

39. In combination, a stretch of railway track, a signal for governing traffic movements in a given 65 direction over said stretch, a second signal for governing traffic movements in a second direction over said stretch, a control relay for said first signal, a time releasing device, a time releasing contact controlled by said device and which at 70 times becomes closed upon the lapse of a measured period of time after the beginning of an operation of said device, a stick relay, a pick-up circuit for said stick relay including a contact operated by said control relay and a contact controlled 75

5 by said first signal and also including a contact controlled by said time releasing device, a stick circuit for said stick relay including a contact operated by said control relay and a contact controlled by said first signal, and means controlled by said stick relay and by said time releasing contact for controlling said second signal.

10 40. In a train dispatching system of the signal indicating type, the combination with a single line circuit and associated apparatus for controlling a distant wayside signal and indicating at the dispatcher's office the passage of a train by such signal, and means for distinctively indicating over the same line circuit the approach of 15 a train toward said signal when such train is approaching the next signal in the rear of such signal.

20 41. A train dispatching system of the wayside signal indicating type comprising, a distant track switch, a power operated switch machine for operating said track switch, a control relay for controlling said switch machine, a simple line circuit for controlling said control relay from a local source of current at a local dispatcher's 25 office, an approach relay and an energizing circuit therefor extending a considerable distance along the track for locking said switch machine against operation by said control relay if there is a train approaching within said distance, and 30 means including said approach relay for indicating at said tower the approach of a train toward said switch machine at said considerable distance.

35 42. In combination with a railway switch, two control relays each arranged when energized to operate said switch to a different position, manually controlled means for energizing a selected one of said relays from a remote point, an indication relay controlled jointly by said switch and by 40 both said relays, and indication means at said remote point controlled by said indication relay.

45 43. In combination with a railway switch, two control relays arranged when energized to operate said switch to different positions, manually controlled means for energizing a selected one of said relays from a remote point, a polarized indication relay, means for energizing said indication relay in one direction when one of said relays is energized provided the switch occupies 50 a corresponding position, means for energizing the indication relay in the opposite direction provided the switch occupies a corresponding position, and indication means at said remote point controlled by said indication relay.

55 44. In an approach locking system, a track switch, a control relay, which if de-energized prevents power operation of said track switch, a detector track relay, an approach relay, and an energizing circuit for said control relay including 60 a back contact of the detector track relay and a front contact of said approach relay.

65 45. In combination, a stretch of railway track divided into a switch section and an approach section, a track switch in said switch section, a detector relay and an approach relay controlled by traffic conditions in said switch section and said approach section respectively, a control relay which if deenergized prevents operation of said switch, and a circuit for said control relay 70 controlled by a back contact of said detector relay and by a front contact of said approach relay.

75 46. In combination with a railway switch, four signals for governing traffic over said switch, a polarized switch control relay, means for operating said switch to one position or the other ac-

cording as said polarized relay is energized in one direction or the other, a polarized signal control relay, means effective when said signal relay becomes energized in one direction or the other, for selectively clearing one of said signals in accordance with the positions of said signal control relay and of said switch, and manually operable means including a single line circuit for selectively energizing either said switch control relay or said signal control relay from a remote point. 10

15 47. In combination with a stretch of railway track having two opposing signals including one at each end of said stretch for governing traffic through said stretch, a manually controlled stick relay for each signal, and interlocked energizing 20 circuits for said signals, the circuit for each signal including a front contact of the stick relay associated with the signal and a back contact of the stick relay associated with the opposing signal.

25 48. In combination with a stretch of railway track having two opposing signals including one at each end of said stretch for governing traffic through said stretch, a pair of manually controlled relays, and interlocked energizing circuits 30 for each of said signals; the circuit for the first signal including a front contact of the first relay of the pair, a connecting wire, a back contact of the second relay, and a source of energy; and the circuit for the second signal including a front 35 contact of the second relay, said wire, a back contact of the first relay and a source of energy.

40 49. In combination with a stretch of railway track having two opposing signals including one at each end of said stretch for governing traffic 35 through said stretch, a manually controlled stick relay for each signal, interlocked energizing circuits for said signals, the circuit for each signal including a front contact of the stick relay associated with the signal and a back contact of the 40 stick relay associated with the opposing signal, and means for preventing either of said signal circuits from becoming closed when said stretch is occupied by a train.

45 50. In combination with a stretch of railway track having two opposing signals including one at each end of said stretch for governing traffic through said stretch, a stick relay for each signal, interlocked energizing circuits for said signals, the circuit for each signal including a front contact of the stick relay associated with the signal and a back contact of the stick relay associated with the opposing signal, manually controlled means for selectively energizing said stick relays, and means rendered effective when a train enters 50 said stretch for releasing said stick relays.

55 51. In combination with a stretch of railway track having two opposing signals including one at each end of said stretch for governing traffic through said stretch, a stick relay for each signal, interlocked energizing circuits for said signals, the circuit for each signal including a front contact of the stick relay associated with the signal and a back contact of the stick relay associated with the opposing signal, a track relay for said 60 stretch, a manually controlled pick-up circuit for each stick relay, and holding circuits for said stick relays each including a front contact of said track relay.

65 52. In combination with a stretch of railway track including a track switch and having two pairs of opposing signals each pair including a signal at each end of said stretch, one pair for governing traffic through said stretch when the switch is normal and another pair for gov- 70

erning traffic through said stretch when the switch is reversed, two pairs of stick relays including a pair of relays for each pair of signals, interlocked circuits for said relays arranged to prevent the energization of either relay of a pair when a relay of the other pair is energized, an energizing circuit for each signal including a front contact of the associated relay, and manually operable means for selectively closing the circuits for said relays.

53. In combination with a stretch of railway track including a track switch and having two pairs of opposing signals each pair including a signal at each end of said stretch, one pair for governing traffic through said stretch when the switch is normal and another pair for governing traffic through said stretch when the switch is reversed, a manually controlled stick relay for each signal, and an energizing circuit 20 for each signal closed only when the corresponding stick relay is energized and the other stick relay of the same pair is deenergized.

54. In combination with a stretch of railway track including a track switch and having two pairs of opposing signals each pair including a signal at each end of said stretch, one pair for governing traffic through said stretch when the switch is normal and the other pair for governing traffic through said stretch when the switch is reversed, a stick relay for each signal, a manually controlled pick-up circuit for each stick relay, a stick circuit for each stick relay, and an operating circuit for each signal closed only when the corresponding stick relay is energized and the other stick relay of the same pair is deenergized.

55. In combination with a stretch of railway track including a track switch and having two pairs of opposing signals each pair including a signal at each end of said stretch, one pair for governing traffic through said stretch when the switch is normal and another pair for governing traffic through said stretch when the switch is reversed, a manually controlled stick relay for each signal, an energizing circuit for each signal closed only when the corresponding stick relay is energized, and electric interlocking means for preventing the energization of more than one of said stick relays at a time.

56. In combination with a stretch of railway track including a track switch and having two pairs of opposing signals each pair including a signal at each end of said stretch, one pair for governing traffic through said stretch when the switch is normal and another pair for governing traffic through said stretch when the switch is reversed, a manually controlled stick relay for each signal, an energizing circuit for each signal closed only when the corresponding stick relay is energized, and electric interlocking means independent of said switch for preventing the circuits for more than one of said signals from being energized at a time.

57. In combination with a stretch of railway track including a track switch and having two pairs of opposing signals each pair including a signal at each end of said stretch, one pair for governing traffic through said stretch when the switch is normal and another pair for governing traffic through said stretch when the switch is reversed, two pairs of stick relays including a relay for each signal, interlocked operating circuits for said signals, the circuit for each signal including a front contact of the stick relay for said signal and a back contact of

the stick relay for the opposing signal of the pair, and manually operable means for selectively energizing said relays.

58. In combination with a stretch of railway track including a track switch and having two pairs of opposing signals each pair including a signal at each end of said stretch, one pair for governing traffic through said stretch when the switch is normal and another pair for governing traffic through said stretch when the switch is reversed, two pairs of stick relays including a relay for each signal, interlocked circuits for said relays and signals arranged to prevent the energization of either relay of a pair when a relay of the other pair is energized and to prevent the energization of either signal of a pair when the relay for the opposing signal is energized, manually operable means for selectively energizing said relays, and means for closing the circuit of each signal when the associated relay is energized.

59. In combination with a stretch of railway track including a track switch and having two pairs of opposing signals each pair including a signal at each end of said stretch, one pair for governing traffic through said stretch when the switch is normal and another pair for governing traffic through said stretch when the switch is reversed, switch control means governed manually from a distant point for operating said switch, signal control means governed manually from a distant point for selectively clearing said signals, and interlocked circuits controlled through the medium of said switch control means for preventing the clearing of a signal except when the route indicated by said signal control means is in agreement with the route indicated by said switch control means.

60. In combination with a stretch of railway track including a track switch and having two pairs of opposing signals each pair including a signal at each end of said stretch, one pair for governing traffic through said stretch when the switch is normal and another pair for governing traffic through said stretch when the switch is reversed, switch control means governed manually from a distant point for operating said switch, signal control means governed manually from a distant point for selectively clearing said signals, and interlocked circuits controlled by said switch control means through the medium of said switch for preventing the clearing of a signal except when the route indicated by said signal control means agrees with the route determined by the position of the switch.

61. In combination with a stretch of railway track including a track switch and having a pair of opposing signals including one at each end of said stretch for governing traffic over said stretch when the switch is normal, and a second pair of opposing signals including one at each end of said stretch for governing traffic over said stretch when the switch is reversed, two polarized signal control relays manually controllable from a remote point including one for each pair of signals, operating circuits for one signal of each pair including a neutral front contact and one polar contact of the associated relay, operating circuits for the other signal of each pair including a neutral front contact and the opposite polar contact of the associated relay, and means for selectively operating said relays.

62. In combination with a stretch of railway track including a track switch and having a pair

of opposing signals including one at each end of said stretch for governing traffic over said stretch when the switch is normal, and a second pair of opposing signals including one at each 5 end of said stretch for governing traffic over said stretch when the switch is reversed, two polarized signal control relays manually operable from a remote point including one for each pair of signals, operating circuits for one signal of each 10 pair including a neutral front contact and one polar contact of the associated relay, operating circuits for the other signals of each pair including a neutral front contact and the opposite polar contact of the associated relay, means for selectively operating said relays, means governed 15 manually from a remote point for controlling said switch, and means controlled by said switch control means through the medium of said switch for preventing the clearing of a signal except 20 when the route established by said signal control relays agrees with the route permitted by said switch.

63. In combination with a stretch of railway track including a track switch and having a 25 pair of opposing signals including one at each end of said stretch for governing traffic over said stretch when the switch is normal, and a second pair of opposing signals including one at each end of said stretch for governing traffic over 30 said stretch when the switch is reversed, two polarized signal control relays manually operable from a remote point including one for each pair of signals, operating circuits for one signal of each pair including a neutral front contact and one polar contact of the associated relay, operating 35 circuits for the other signals of each pair including a neutral front contact and the opposite polar contact of the associated relay, means for selectively operating said relays, and means controlled by said switch for preventing the clearing of a signal except when the route established by said signal control relays agrees with the route permitted by said switch.

64. In combination with a detector section of 45 railway track including a track switch, a signal governing the movement of traffic through said section, an approach track section traversed by traffic approaching said signal, a stick relay adapted to be energized only when said signal indicates stop, selecting means controlled from a 50 distant point for operating the switch, means for preventing operation of the switch by said selecting means except when said stick relay is energized and the detector section is unoccupied, a pick-up circuit for the stick relay closed only 55 when the detector section is occupied, a second pick-up circuit for said stick relay closed only when the approach track section is unoccupied, a third pick-up circuit for said stick relay, a slow-acting device adapted to consume a time 60 interval in moving from a reverse to a normal position, means requiring said device to be in its normal position to clear said signal, and a contact included in the third pick-up circuit for said stick relay closed only when said slow-acting 65 device is in its reverse position.

65. In combination with a railway switch, a signal governing traffic over the switch, selecting means manually controlled from a distant 70 point for operating the switch and the signal, a slow-acting device, locking means effective at times to prevent an operation of the switch after the signal changes from a proceed to a stop indication, means controlled by said slow-acting device when operated to release said locking 75

means, and checking means controlled by said slow-acting device for preventing the operation of the signal from a stop to a proceed indication until said slow-acting device has been restored to its normal position. 5

66. In combination with a railway switch, a signal governing traffic over the switch, an approach locking relay adapted to be energized only when the signal indicates stop, selecting means controlled from a distant point for clearing 10 the signal and for also operating the switch provided the approach locking relay is energized, a slow-acting device adapted to consume a time interval when operated, means for picking up the approach locking relay when the signal is 15 put to stop provided no train is approaching within a predetermined distance of said signal, means for picking up said approach locking relay when the signal is put to stop and said slow-acting device is operated, and checking means 20 controlled by said slow-acting device for preventing the operation of said selecting means except when said slow-acting device occupies its normal position.

67. In combination with a detector section of 25 railway track including a track switch, a signal governing the movement of traffic through said section, means for manually governing said signal, an approach track section traversed by traffic approaching said signal, a stick relay 30 adapted to be energized only when said signal indicates stop, selecting means controlled from a distant point for operating the switch, means for preventing operation of the switch by said selecting means except when said stick relay is 35 energized and the detector section is unoccupied, a pick-up circuit for the stick relay closed only when the detector section is occupied, a second pick-up circuit for said stick relay closed only when the approach track section is unoccupied, a slow-acting device adapted to consume a time 40 interval when operated, a third pick-up circuit for said stick relay closed when said slow-acting device is in its reverse position, and checking means controlled by said slow-acting device for 45 preventing the operation of said signal to cause it to display a proceed indication except when said slow-acting device occupies its normal position.

68. In combination with a detector section of 50 railway track including a track switch, a signal governing the movement of traffic through said section, and an approach track section traversed by traffic approaching said signal, a stick relay adapted to be energized only when said signal 55 indicates stop, selecting means controlled from a distant point for operating the switch, means for preventing operation of the switch by said selecting means except when said stick relay is energized and the detector section is unoccupied, a pick-up circuit for the stick relay closed only when the detector section is occupied, a second pick-up circuit for said stick relay closed only when the approach track section is unoccupied, a manually operable releasing device 60 having a normal and a reverse position, a third pick-up circuit for said stick relay closed only when said device is in its reverse position, and checking means for preventing the operation of said signal to cause it to display a proceed indication except when said slow-acting device occupies its normal position. 65

69. In combination with a section of railway track, a signal for governing traffic over said section, a track relay for said section, two stick 70

5 relays, a holding circuit for each stick relay one such circuit but not the other including a front contact of said track relay, means controlled from a distant point for selectively energizing said 5 stick relays, and means for selectively energizing said signal in accordance with the condition of said stick relays.

10 70. In combination with a section of railway track, a signal for governing traffic over said section, a track relay for said section, two stick 10 relays, a holding circuit for each stick relay one such circuit but not the other including a front contact of said track relay, means controlled from a distant point for selectively energizing said 15 stick relays, and means for manually controlling said signal through the medium of said stick relays, whereby said signal may optionally be controlled by a stick relay responsive to the movement of a train past said signal, or by a 20 stick relay independent of traffic conditions adjacent said signal.

15 71. In combination, a section of railway track, a signal governing traffic through said section, two stick relays, manually operable means controlled from a distant point for selectively energizing said 25 stick relays, a stick circuit for each stick relay, means for causing the signal to indicate proceed when either of said stick relays is energized, and means for automatically opening the stick circuit for one stick relay but not the other when a train enters said section.

20 72. In combination with a section of railway track, a signal for governing traffic over said section, a track relay for said section, a manually controlled stick relay, means for energizing said signal when said stick relay is energized, a holding circuit for said stick relay including a front contact of said track relay, and other manually controlled means for energizing said 25 signal even though said holding circuit is opened by the passage of a train through said section.

25 73. In combination with a stretch of railway track containing a power operated track switch, a signal governing traffic over said switch, a circuit controller located adjacent said stretch and capable of assuming two positions, means controlled from a remote point for operating said circuit controller to one or the other of said 30 positions, means requiring said circuit controller to be in one position for actuating said power operated switch to normal or reverse, and means requiring said circuit controller to be in the other position for causing said signal to indicate proceed.

35 74. In combination with a stretch of railway track containing a power operated switch, a signal governing traffic over said switch, a manually controlled circuit controller capable of assuming two positions, means requiring said circuit controller to be in one position for actuating said power operated switch to normal or reverse, means requiring said circuit controller to be in another position to clear said signal, and time measuring means for at times delaying the movement of said circuit controller to said other position.

40 75. In a train dispatching system, means for controlling a railway switch and a signal governing train movements over said switch from a remote office, approach locking means for preventing operation of said switch if a train enters an approach zone when the signal which said train is approaching indicates proceed but which will not prevent operation of said switch if a 45 train enters such zone while said signal indicates

stop, means for indicating at said office the presence of a train in said approach zone, and for indicating the position of said signal.

5 76. In combination, a railway track switch, a signal for governing traffic movements over said switch, a control circuit for said signal, a first stick relay, a manually controlled pick-up circuit for said first stick relay, a stick circuit for said first stick relay controlled by said signal control circuit and by traffic conditions, a second stick relay, a pick-up circuit for said second stick relay controlled by traffic conditions and by said first stick relay, a stick circuit for said second stick relay controlled by said first stick relay, and means controlled by said second stick relay for controlling said switch.

10 77. An electrical train indicating system comprising a series of track circuits, an indicator circuit comprising a source of current and electrical resistance, and relays controlled by the track circuits and in turn controlling said electrical resistance to vary the amount thereof in said indicator circuit.

15 78. In a system for determining the location of a railroad train, a stretch of track for the train divided into sections, a circuit electrically separated from said track, a device connected with said circuit for each section, each of said devices, when operated by a train in its section, automatically affecting the electrical characteristics of said circuit differently, and means in said circuit responsive to the changes of the electrical characteristics of said circuit.

20 79. In a system for determining the location of a railroad train, a stretch of track for the train divided into sections, a circuit insulated from said track, means connected to said circuit for each section controllable by a train in said section for changing the characteristics of said circuit, the means for adjacent sections, when controlled, being adapted to affect said circuit differently, and means in said circuit responsive to changes in said characteristics.

25 80. In a system for determining the location of a railroad train, a stretch of track for the train divided into sections, a circuit electrically separated from said track, a source of energy in said circuit, means connected with said circuit for each section controllable by a train in said section for changing the current in said circuit, the means for adjacent sections, when controlled, being adapted to change said current differently, and means in said circuit responsive to said current and said current as changed.

30 81. In a train dispatching system for railroads, a central office and a distant station connected by line wires, a section of railway track at said station provided with a track circuit including a track relay, an indication relay at said office having two energized positions in addition to a normal deenergized position, means operating over said line wires for controlling said indication relay from said station and including means for momentarily operating the indication relay to one energized position when said track relay becomes deenergized and for momentarily operating the indication relay to the other energized position when said track relay becomes energized, two indication control circuits at said office including contacts closed when said indication relay occupies said two energized positions respectively, two visual indicators one for each said circuit and each arranged to be actuated when the associated circuit is closed and to remain actuated after the associated circuit is opened but to be restored.

to normal when the other circuit becomes closed, and a single stroke gong located at the office and operated momentarily when one of said indicators becomes actuated to call attention to the change 5 in the condition of the track section at the station.

82. In a centralized traffic controlling system for railroads, a track section including a track switch, a switch machine for operating said track switch, relay means for governing said switch machine, control means at a remote point for governing said relay means, means for preventing operation of the switch when said track section is occupied even though said control means is 10 operated, a polarized indication circuit having current flowing in one direction with the track switch in one position and with said relay means in correspondence therewith and having current flowing in the opposite direction with the track 15 switch in an opposite position and with said relay means in correspondence therewith but having no current therein when said relay means and said track switch are out of correspondence, and indication means included in said indication circuit.

83. In a centralized traffic controlling system for railroads, a track section including a track switch, a switch machine for operating said track switch, relay means for governing said switch machine, control means at a remote point for governing 30 said relay means, means for preventing operation of the switch when said track section is occupied even though said control means is operated, a polarized indication circuit having current flowing in one direction with the track switch 35 in one position and with said relay means in correspondence therewith and having current flowing in the opposite direction with the track switch in an opposite position and with said relay means in correspondence therewith but having no current 40 therein when said relay means and said track switch are out of correspondence, indication means included in said indication circuit, and a signal controlled by said indication means.

84. In a centralized traffic controlling system for railroads, a track section including a track switch, a switch machine for operating said track switch, relay means for governing said switch machine, control means at a remote point for governing 45 said relay means, means for preventing operation of the switch when said track section is occupied even though said control means is operated, a polarized indication circuit having current flowing in one direction with the track switch 50 in one position and with said relay means in correspondence therewith and having current flowing in the opposite direction with the track switch in an opposite position and with said relay means in correspondence therewith but having no current 55 therein when said relay means and said track switch are out of correspondence, indication means included in said indication circuit, and a signal at said remote point controlled by said indication means.

85. In combination, a railway track switch, a signal for governing traffic movements over said switch, a control circuit for said signal, a stick relay, a pickup circuit for said relay controlled by traffic conditions, a stick circuit for said relay controlled by said signal control circuit, and an 60 indication means controlled by said relay.

86. In combination, a track switch of a railway system, a switch machine for operating said switch, a signal associated with said switch for governing movement of traffic over said switch, and a two-position contact which if in one 75 position

closes a circuit for clearing said signal and when in the other position closes a circuit for controlling said switch machine, whereby said switch machine can not be operated unless said signal is at stop. 5

87. In combination, a track switch of a railway system, a switch machine for operating said switch, a plurality of signals associated with said switch for governing movement of traffic over said switch, and a two-position contact which if in one position closes a circuit for clearing any one of said signals and when in the other position closes a circuit for controlling said switch machine, whereby said switch machine can not be operated unless all of said signals are at stop. 10 15

88. In combination, a track switch of a railway system, a switch machine for operating said switch, a signal associated with said switch for governing movement of traffic over said switch, a two-position contact which if in one position 20 closes a circuit for controlling said signal to stop and when in the other position closes a circuit for controlling said switch machine, and timing means for delaying the movement of said contact to said other position, whereby said switch 25 machine can not be operated until after a lapse of time after said signal has been put to stop.

89. In combination, a track switch of a railway system, a switch machine for operating said switch, a plurality of signals associated with said switch for governing movement of traffic over said switch, a two-position contact which if in one position closes a circuit for controlling any one of said signals to stop and when in the other position closes a circuit for controlling said 30 switch machine, and timing means for delaying the movement of said contact to said other position, whereby said switch machine can not be operated until said signals have been at stop for a predetermined period of time. 35 40

90. In combination, a track switch, a switch machine for operating said track switch, a signal for governing movement of traffic over said track switch, a signal relay which if energized permits clearing of said signal, a switch machine relay 45 for controlling said switch machine, two levers one for energizing said signal relay and the other for energizing said switch machine relay, and a contact in the control circuit of said switch machine relay closed only if said signal control relay 50 is deenergized.

91. In combination with a railway signal capable of displaying either a first or a second indication, a control circuit for said signal including a resistance unit and a source of current, 55 a manually operable device, means controlled by said manually operable device for at times forming a shunt path around said resistance unit in said circuit, means for causing said signal to display said first indication when said resistance unit is included in said circuit, means for causing said signal to display said second indication when said shunt path is formed around said resistance unit in said circuit, and means for causing said signal to continue to display said second indication after said shunt path has been opened. 60 65

92. In combination with a railway signal capable of displaying either a normal proceed indication or a call-on indication, a home relay, a call-on relay responsive only to current of 70 greater magnitude than that which is required for the operation of said home relay, a resistance unit, a circuit including said home and call-on relays and said resistance unit in series, a manually operable contact by which a shunt 75

path of low resistance can be closed around said resistance unit in said circuit, a source which while said shunt path is open supplies said circuit with current of sufficient magnitude to operate said home relay but not said call-on relay, but which source while said shunt path is closed supplies said circuit with current of sufficient magnitude to operate said call-on relay as well as said home relay, means for controlling 5 said normal proceed signal indication by said home relay, and means for controlling said call-on signal indication by said call-on relay.

93. In a railway switch and signal control layout, the combination with a distant track switch, 15 a signal associated with said track switch, a detector track circuit for said switch, a line circuit connecting a local dispatcher's office and said layout for controlling said signal subject to traffic conditions ahead, an approach section 20 separate from said detector track circuit, means for preventing operation of said track switch when said approach section is occupied unless it became occupied after said signal was put to stop, and means independent of said signal for 25 indicating occupancy of said approach section over said line circuit.

94. In a railway switch and signal control layout, the combination with a distant track switch, a switch machine for controlling said 30 switch, a signal associated with said track switch, a detector track circuit for said switch, a line circuit connecting a local dispatcher's office and said layout for controlling said switch machine and controlling said signal subject to traffic conditions ahead, an approach section separate from 35 said detector track circuit, means for preventing operation of said track switch when said approach section is occupied unless it became occupied after said signal was put to stop, and means independent of said signal for indicating occupancy 40 of said approach section over said line circuit.

95. In combination, a plurality of electroresponsive devices, a manually operable device, a second manually operable device operated independently of said first manually operable device, a stick relay, a pick-up circuit for said stick relay controlled by said first manually operable device, a stick circuit for said stick relay controlled by 45 said second manually operable device, and means controlled by said stick relay for energizing said electroresponsive devices successively.

96. In combination, a circuit extending between two electroresponsive signal operating mechanisms respectively associated with the opposite ends of a section of railway track over which traffic is to move in either direction, a current source at each end of the circuit for supplying current to said circuit but normally disconnected 50 therefrom, a central office controlled relay associated with each end of the circuit, means governed by each central office controlled relay when energized to connect the associated current source with said circuit, and signals governed by 55 said mechanisms to permit traffic to move through the section in a direction determined by the end at which said circuit is supplied with current.

97. In combination, a stretch of track, a signal at each end of said stretch for governing the 70 movement of traffic into said stretch from that end, an electroresponsive mechanism associated with each of said signals which when energized causes the associated signal to indicate proceed, a relay manually controlled from a central office 75 associated with each of said signals, a movable

contact on each of said relays, said movable contacts being connected by a partial circuit and said movable contacts if in one position connecting said partial circuit to the associated electroresponsive mechanism and if in another position connecting said partial circuit to a source of current, whereby both of said mechanisms may be controlled over the same partial circuit and only one of said mechanisms may be energized at one time. 10

98. In combination, a railway track switch, a signal for governing traffic movements from a given direction over said switch, a second signal for governing traffic movements from said given direction toward said first signal, an approach 15 locking relay, a pickup and a stick circuit for said relay one of which is controlled by said first signal and the other of which is controlled by said second signal and by track conditions, and means controlled by said relay for controlling 20 said switch.

99. In combination, a railway track switch, a signal for governing traffic movements from a given direction over said switch, a second signal for governing traffic movements from said given 25 direction toward said first signal, a locking relay, a pickup and a stick circuit for said relay one of which is controlled by said first signal and the other of which is controlled by said second signal, and means controlled by said relay for controlling 30 said switch.

100. In combination, a railway track switch, a signal for governing traffic movements over said switch, a stick relay, a slow acting device having a normally open contact and a normally closed 35 contact which remains open for a measured interval of time when said device is operated to close said normally open contact, means controlled by said normally closed contact for controlling said signal, a pick-up circuit for said relay controlled by said normally open contact, a stick circuit for said relay controlled by said signal, and means controlled by said relay for controlling said switch. 40

101. In combination, means for controlling a 45 switch machine in accordance with the polarity of current of a particular character transmitted wholly over a single line circuit from a source at a central office and for transmitting an indication to said central office by current of the same 50 character over said line circuit but from a source at said way station and having a polarity corresponding to the position of said switch machine.

102. In a dispatching system of the type described, the combination with signals at the end 55 of a passing siding governing traffic in opposite directions in accordance with the position of the switch, two stick relays adjacent said switch governing said signals, one stick relay controlling the other, and means operable from a distant point for controlling said stick relays. 60

103. In a dispatching system of the type described, the combination with signals at the end of a passing siding governing traffic in opposite directions in accordance with the position of the 65 track switch, two stick relays governing said signals, one stick relay having a back contact included in the energizing circuit of the other stick relay, and means operable from a distant point for controlling said stick relay. 70

104. In combination, a traffic governing device having different control conditions, a normally deenergized relay for governing the operation of the device, a control circuit to energize said relay for causing an operation of the device, means 75

effective upon the completion of an operation of the device to deenergize said relay, and indication means governed in accordance with the condition of the device and rendered ineffective upon the release of said relay.

105. In combination, a stretch of railway track including a track switch, a polarized indication device, means controlled by said switch for supplying current of a given polarity to said device, and means controlled in accordance with track circuit conditions in said stretch for supplying current of the opposite polarity to said device.

106. In combination, a stretch of railway track including a track switch, a signal for governing traffic movements over said switch, a manually controlled signal control relay, means controlled by said signal control relay for controlling said signal, a switch locking relay having a pickup and a stick circuit one of which is controlled by said signal and by said signal control relay and the other of which is controlled by traffic conditions in at least a portion of said stretch, and switch control means controlled by said locking relay for controlling said switch.

107. In combination, a stretch of railway track including a track switch, a signal for governing traffic movements over said switch, a manually controlled signal control relay, means controlled by said signal control relay for controlling said signal, a manually controlled device, a switch locking relay having a pickup and a stick circuit one of which is controlled by said signal and by said signal control relay and the other of which is controlled by said manually controlled device, and switch control means controlled by said locking relay for controlling said switch.

108. In combination, a stretch of railway track including a track switch, a signal for governing traffic movements over said switch, a signal control relay, means including a front contact of said signal control relay for controlling said signal, a switch locking relay having a pickup and a stick circuit one of which is controlled by said signal and includes a back contact of said signal control relay and the other of which is controlled by traffic conditions in at least a portion of said stretch, and means controlled by said locking relay for controlling said switch.

109. In combination, a two-position relay, a slow pickup slow-release repeating relay controlled by said two-position relay, and means controlled jointly by said relays for briefly transmitting to a remote point one distinctive indication when said two-position relay picks up and a different distinctive indication when said two-position relay releases.

110. In combination, a section of railway track, a track relay for said section, a slow pickup slow-release repeating relay controlled by a front contact of said track relay, an indication circuit including a front contact of said track relay and a back contact of said repeating relay, a second indication circuit including a back contact of said track relay and a front contact of said repeating relay, and means responsive to the momentary closing of said circuits for continuously indicating the condition of said track section.

111. A train dispatching system of the way-side signal indicating type comprising, a distant track switch, a power operated switch machine for operating said track switch, a control relay for controlling said switch machine, a simple line circuit for controlling said control relay from a local source of current at a local dispatcher's office, and means for distinctively indicating by separate indicators the passage of a train over said switch and the approach of a train toward said switch over said line circuit.

112. In a train dispatching system, the combination with a line circuit connecting a dispatcher's office and a distant railway signal including a control relay connected in series in said line circuit at the signal end of said circuit and a manually operable lever having a contact connected in series with a source of current at the office end of said circuit, of another contact on said lever closed when said first-mentioned contact is open and which if closed includes an indicating relay in said circuit at the office end of said circuit, means effective if there is a train approaching within a predetermined distance of said signal for including a source of current in said line circuit at said signal end of said circuit to energize said indicating relay, and an indicator controlled by said indicating relay.

HERBERT A. WALLACE.
